UNITED STATES PATENT OFFICE.

TREVELYAN SHARP, OF MANCHESTER, ENGLAND.

APPARATUS FOR COMPRESSING SCRAP METAL.

No. 823,703.

Specification of Letters Patent.

Patented June 19, 1906.

Application filed March 30, 1903. Serial No. 150,278.

To all whom it may concern:

Be it known that I, TREVELYAN SHARP, a subject of the King of Great Britain and Ireland, residing at Manchester, in the county of 5 Lancaster, England, have invented new and useful Improvements in Apparatus for Compressing Scrap Metal, of which the following is a specification.

This invention relates to apparatus for 10 compressing scrap metal into blocks or slabs; and its primary object is the reduction of the number of rams necessary in other machines constructed for the like purpose. By these 15 improvements the general construction of such apparatus is greatly simplified, while its efficiency is increased.

The improved apparatus consists, essentially, in a cast-iron box having three fixed walls, one reciprocable wall, and a slide-lid. 20 Two rams only are required, as compared with four or five rams in existing apparatus—a horizontal ram for compressing the material into a smaller compass by pushing the reciprocable wall forward and a vertical ram for 25 further compressing the material from above.

The accompanying drawings illustrate my present improvements and will be hereinafter referred to.

Figure 1 shows a side elevation; Fig. 2, a 30 plan with the vertical ram removed; Fig. 3, an end elevation, and Fig. 4 a cross-section taken through the box in which the compression of the scrap metal takes place.

The box *a*, in which the metal is compressed, is constructed of cast-iron, has three 35 fixed walls and a reciprocable end wall *b*, to which motion is given by the hydraulic ram *c*. The slide cover or lid *d* is movable to and fro in the guide-rails *d'* and can be moved in 40 one direction, so as to inclose the box-cavity, and in the other direction, so as to completely uncover it. As shown by the drawings, it passes through a slot in the upper part of the back wall and may be prevented from rising 45 when pressure is applied by internal flanges on the tops of the walls. Its motion can be effected manually or mechanically. The inner face of the wall *b* and of the back wall are so constructed, as shown by Fig. 2, that when 50 the wall *b* is pushed into the box to the limit of its travel there is inclosed between the two parts the rectangular space *e*, diagonal to the sides of the box, into which the metal is finally compressed. To accomplish this and 55 also to direct any scrap metal inwardly in the box, and thus prevent it being jammed be-

tween the ram or movable wall *b* and the adjacent walls of the box, the face of the ram *b* is inclined diagonally across the box or press for the greater part of its length, and where it 60 forms an acute angle with the box a reentering lip or shelf is disposed to also direct the scrap inward at that edge. The end wall of the box and two of the faces of the vertically-moving ram are disposed parallel to the inclined face of the ram *b*. In Fig. 2 a part of the slide-cover *d* is shown to be broken away, so as to disclose this rectangular space, which is indicated by broken section-lines. Over this part of the box the vertical ram is 65 arranged, the horizontal ram being arranged at the back or outer side of the wall *b*.

When the apparatus is to be used, the box is fully open and both rams withdrawn. The box is filled with the scrap metal and the 70 slide-cover *d* is pushed over the box into contact with the wall *b*, against which it is shaped to fit. The hydraulic ram *c* is now put into action and gradually pushes forward and compresses the mass of metal, at the same 75 time pushing with it the cover *d*, which prevents the rising of the metal. When the ram *c* has arrived at the limit of its stroke, the slide-cover is withdrawn from over the space 80 *e*, into which the whole of the metal has now 85 been compressed and becomes supported by the guide-rails of the frame *f*. The vertical ram *h*, which has a head of rectangular cross-section adapted to fit into the space *e*, is now caused to descend and to complete the compression of the metal in that space. The rams are then withdrawn and the block of 90 compressed metal is removed, after which the operation is repeated with a fresh supply of metal.

The cylinder *g* of the ram *h* in the construction illustrated is carried on the cross-head *s*, which is supported by four vertical columns. The cylinder *c'* of the ram *c* is fixed on a bed 95 which is bolted to the box *a* at its front end and is additionally secured thereto by means of a lug *n* on the cylinder, a cross-rail *m* at the back of the lug, and two straps *o o*, bolted to the box *a*.

Below the box there is a cavity *h'*, through 105 which water may be circulated to keep the box cool when in use. The travel of the ram *c* may be limited by adjustment of screw-nuts *i* upon the screw-threaded outer end of the check-rod *i*, whose inner end is secured to the 110 ram *c*.

To avoid confusion in the drawings, the

water-service for the hydraulic rams has been omitted, its construction and arrangement being well known and understood. The return strokes of the rams may be made under water-pressure or under the influence of the weights $w w$, as is also well understood.

Although I have described pressure as being applied to the metal by hydraulic rams, I desire it to be understood that I do not limit myself to this means, since other means for applying the requisite pressure, such as screws, may be used.

What I do claim as my invention, and desire to secure by Letters Patent, is—

15 1. An apparatus for compressing scrap metal consisting of a box having three fixed walls, a sliding cover, a movable wall or ram which engages with and moves the sliding cover with it during the compression-stroke 20 of the ram, and a second ram at right angles to the first and operating to complete the compression of the scrap, substantially as set forth.

25 2. In apparatus for compressing scrap metal, a box having a sliding cover and three fixed sides, in combination with a ram to compress the scrap under the cover, said ram engaging with the sliding cover and moving it with it during the compression-stroke, and 30 a second ram moving at right angles to the

first to further compress the scrap after the cover has been withdrawn from the box, the faces of the rams and the inner face of the end of the box forming a diagonal chamber in the end of the box, substantially as described.

35

3. In an apparatus for compressing scrap metal, the combination of a compression-box having an inclined face at its inner end, a sliding cover, a main ram having an inclined face abutting against one end of said sliding cover, and a secondary or final ram to complete the compression of the scrap, the faces of the two rams and the inclined face at the inner end of the compression-box forming a diagonal chamber in the end of said box.

45

4. In apparatus in which scrap metal is compressed in a box by two rams having their axes at right angles, the combination with the box and with the horizontal ram, of a sliding cover which is engaged by and moves with the horizontal ram during the compression-stroke and under which compression is effected.

50

In testimony whereof I have signed my name to this specification in the presence of 55 two subscribing witnesses.

TREVELYAN SHARP.
